UNITED STATES PATENT OFFICE.

ERNEST MEYERS, OF TAUNTON, MASSACHUSETTS, ASSIGNOR TO REED & BARTON CORPORATION, OF TAUNTON, MASSACHUSETTS, A CORPORATION OF MASSACHUSETTS.

DESIGN FOR A HANDLE FOR SPOONS, FORKS, OR SIMILAR ARTICLES.

SPECIFICATION forming part of Design No. 35,860, dated April 15, 1902.

Application filed March 21, 1902. Serial No. 99,385. Term of patent 14 years.

To all whom it may concern:

Be it known that I, ERNEST MEYERS, a citizen of the United States, and a resident of Taunton, in the county of Bristol and State of Massachusetts, have invented and produced a new and original Design for a Handle for Spoons, Forks, or Similar Articles, of which the following is a specification, reference being had to the accompanying drawing, forming part hereof.

Said drawing represents a front view of a spoon or fork handle, exhibiting my new and original design. From the narrow part of the shank of the handle, at about the point marked *a*, there are developed in relief reed-like or tendril-like forms, (shown in the drawing at *b*,) from which appear to be springing the forms of foliated stalks bearing buds. These foliated stalks *c* and buds *d d'* are also in relief and, as shown in the drawing, are of the form and character of the fronds and buds, respectively, of a chrysanthemum. Above the said bud ornamentations *d d'*, at about the junction of the shank with the handle proper and at one side of the median line of the handle, the design develops a flower figure or blossom, also in bas-relief, while beside said flower figure or blossom and on the other side of said median line are other

buds, also in relief. Said flower figure or blossom and said last-mentioned buds, as shown in the drawing at *e* and *ff'*, respectively, are of the form and character of a chrysanthemum blossom and buds. The blossom, buds, and foliage ornamentation, which accompanies them and assists in the composition, are sufficiently conventionalized to conform to the general outline of the handle of the article to which they are applied. Above the blossom and bud ornamentation *e* and *ff'* and around the edge of the broad part of the handle the design develops the fillets *g* and *g'*, overlying which are the foliate figures *h* and *h'*, rising from behind the blossom and buds *e* and *ff'*. At the end of the handle is another bud-figure. (Shown in the drawing at *i*.)

What I claim, and desire to secure by Letters Patent, is—

The design for a handle for spoons, forks or similar articles, substantially as shown and described.

Signed by me at Taunton this 18th day of March, 1902.

ERNEST MEYERS.
